UNITED STATES PATENT OFFICE.

ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

WARP STOP-MOTION FOR LOOMS.

No. 885,179.

Specification of Letters Patent.

Patented April 21, 1908.

Application filed August 24, 1907. Serial No. 389,928.

To all whom it may concern:

Be it known that I, ALONZO E. RHOADES, a citizen of the United States, and resident of Hopedale, county of Worcester, State of Massachusetts, have invented an Improvement in Warp Stop-Motions for Looms, of which the following description, in connection with the accompanying drawing, is a specification, like letters on the drawing, representing like parts.

This invention has for its object the production of novel means for effecting automatically the stoppage of a loom by or through failure of a warp-thread.

In the present embodiment of my invention the release of a drop-device or detector by such warp failure arrests a vibratable feeler, and acts through a controller to operatively position a normally quiescent and inoperative member, to be engaged by a moving part of the loom, such engagement effecting release of the shipper. The means for controlling the said normally quiescent member and for effecting the vibrations of the feeler form novel features of my invention, and I have also made a novel feeler construction whereby the movement thereof is effected very easily and with but little power.

I have so constructed and arranged the mechanism that when a released detector engages and arrests the feeler the strain upon such detector will be very slight indeed.

The various novel features of my invention will be fully described in the subjoined specification and particularly pointed out in the following claims.

Figure 1 is a transverse sectional view of a sufficient portion of a loom, with one embodiment of my present invention applied thereto, the stop motion mechanism being shown in normal position, as when the loom is running properly; Fig. 2 is a detail of a portion of the apparatus shown in Fig. 1, but in abnormal position and in readiness to effect loom stoppage; Fig. 3 is a cross-sectional detail on the line 3—3, Fig. 1, looking toward the left.

Referring to Fig. 1 I have shown a portion of the shipper 1, a knock-off or releasing lever 2 therefor, a lay 3 and usual lay-swords 4 (one being shown), and a cam-shaft 5, all of which may be of any suitable and

well known construction, operating in usual manner. Upon the cam-shaft 1 fixedly mount a cam 6 coöperating with a follower 7 fast on a short rock-shaft 8 mounted on the loom-frame and having a fixedly attached upturned arm or actuator 9, which is vibrated by coöperation of the follower and cam as the latter rotates. It will be understood that the vibrating actuator will swing back and forth while the loom is running, making one complete movement for every two beats of the lay.

I have shown the upper end of the actuator as bifurcated, at 10, see Fig. 3, to receive preferably a roll or sleeve 11, adapted to normally enter a bevel-sided seat 12 in a controller 13, forming a slip connection between the controller and actuator. Said controller is, by means of such connection, normally reciprocated by the vibrating movement of the actuator, the weight of the controller being sufficient to maintain the roll in the seat when the loom is running properly. At its forward end the controller has pivotally connected with it at 14 an elongated finger 15, sustained in proper position by a spring 16 interposed between the finger and a lug 17 on the controller, the latter and the finger moving back and forth in a substantially horizontal path, as will be manifest. The rear end of the controller is connected by a light rod or link 18 with a depending arm 19 fast on a rock-shaft 20, Fig. 1, mounted at each end in a suitable bracket 21 on the loom-side, the rock-shaft extending across the loom below the warp and having attached depending arms as 22, to the lower ends of which is secured a feeler 23. Said arms 22 form swinging supports for and by which the feeler is suspended, said feeler being vibrated in a fixed path by and in unison with the reciprocating movement of the controller 13. The controller is held from lateral displacement by the sides of the bifurcated portion 10 of the actuator, and positioned in such portion by its connection 18 with the feeler rock-shaft.

I have shown herein two banks or series of drop devices or detectors 24, of any suitable construction, preferably made of thin sheet metal and each having a warp-eye 25, and a longitudinal slot 26 to receive a support 27

extended across the loom and fixed at its ends in the brackets 21. The detectors are suspended each from a single warp-thread, between the lease-rods L, L', and their lower ends are shown as slightly prolonged, at 28, Fig. 1, but normally the prolongations are held above or out of the feeler path. When a warp-thread fails its detector is released and drops on its support 27, the prolongation 10 28 engaging and arresting the feeler 23, and immediately the arm 19 and connection 18 act to stop reciprocation of the controller 13. The actuator 9 continues its movement, however, and the roll 11 travels along one of 15 the beveled sides of the seat 12 and out of the seat, as will be apparent, lifting and moving transversely the controller as it is thus disconnected from the actuator. Such lifting of the controller is effected on either stroke 20 of the actuator, the stoppage of the controller being effected when a released detector in either of the two series engages the feeler. The vibrating movement of the suspended feeler 23 is effected with very little 25 power, as the constant tendency of the feeler and other parts is to return to mid-position by gravity, and the arm 19 permits a long leverage to rock the shaft 20.

Inasmuch as the controller 13 is of light 30 weight it will be manifest that very slight resistance to its normal reciprocating movement will cause disengagement of the actuator, the roll 11 sliding easily along the beveled side of the seat 12, so that when a detector 35 engages the feeler the pressure upon said detector is reduced to a very small amount, obviating any tendency to bend or distort the detector. The transverse movement of the controller is made effective to 40 cause release of the shipper 1 and consequent stoppage of the loom, and I will now explain the means whereby shipper release is effected. The knock-off lever 2 has connected with it an arm 29, see dotted lines Fig. 1, to which is 45 attached one end of a link 30 extended rearwardly and at its other end pivotally connected with an upturned arm 31 fast on a rock-shaft 32 mounted in a bearing on a bracket 33 on the loom side. Said rock-shaft 50 at its inner end has secured to it a second arm or rocking carrier 34, upon the upper end of which is pivotally mounted a dog 35 provided with a depending lug 36 which rests upon the extended finger 15 of the controller 13. Referring to Fig. 1 it will be seen that the controller is thus in sliding engagement with the dog and sustains the latter in a certain position while said carrier reciprocates, so that the dog is quiescent and at such 55 time it is out of the path of movement of a bunter 37, herein shown as mounted on the lay-sword 4.

When warp failure arrests the feeler and stops reciprocation of the controller the latter 60 is moved transversely and lifted as the roll 11

rides out of the seat 12, and the dog 35 is swung upward on its pivot 35^X, see Fig. 2, and into the path of the bunter. Thereupon the lay as it completes its backward stroke will cause the bunter to push against and longitudinally of the dog, and the carrier 34 will be swung back, acting through the arm 31 and link 30 to throw the knock-off lever 2 and release the shipper. There is no appreciable movement of the dog so long as the loom is running properly, and hence nothing tends to move the dog from its inoperative position into the bunter path until a warp fault occurs and the movement of the feeler is arrested.

I yieldingly support the finger 15 on the controller in order to prevent breakage if, for instance, the lay should be back and the weaver found it necessary to swing the feeler by hand, the loom being at rest. At such time the bunter would be above the dog and would prevent lifting of the latter as the weaver caused longitudinal movement of the controller, but the spring 16 will give and permit the finger to descend a sufficient distance. The rear end of the finger extends back of its pivot and rests on the top of the controller, as shown, Figs. 1 and 2, so that the spring-induced upward movement of the finger is thereby limited, it being understood that save in an exceptional instance such as above referred to the finger moves as if it were an integral or rigid part of the controller.

The means for effecting feeler vibration 100 herein shown dispenses with the use of springs, and the structure is simple, positive in its action, and quickly responsive to abnormal conditions.

Having fully described my invention, what I claim as new and desire to secure by Letters Patent is:-

1. In a loom having a lay and a bunter movable therewith, a shipper, and a releasing device therefor, in combination, stop-motion detectors normally suspended from intact warp-threads, a normally quiescent dog operatively connected with the releasing device, to actuate the same when engaged by the bunter, a normally moving controller 110 in sliding engagement with the dog, and means to effect a change in the position of the controller when a detector is released by its warp-thread, to thereby move the dog into the path of the bunter.

2. In a loom having a shipper, in combination, shipper-releasing means including a normally quiescent and inoperative member, a vibrating member to at times coöperate therewith and effect the release of the shipper, a normally moving controller in sliding engagement with and supporting the quiescent member, and means to effect a change in the position of the controller and thereby cause the coöperation of the vibrat- 125 130

ing member and the normally quiescent member by or through failure of a warp-thread.

3. In a loom, in combination, stop-motion controlling-detectors suspended from intact warp-threads, a shipper, releasing means therefor including a normally quiescent and inoperative dog, a vibrating bunter to coöperate with the dog when operatively positioned and effect the actuation of the shipper-releasing means, a normally moving controller in sliding engagement with the dog, and means to effect a change in the position of the controller and thereby operatively position the dog with respect to the bunter when a detector is released by its warp-thread.

4. In a loom, in combination, stop-motion controlling-detectors suspended from intact warp-threads, a shipper, releasing means therefor including a normally quiescent and inoperative dog, and a rocking carrier upon which it is pivoted, a vibrating bunter to engage the dog when operatively positioned and rock the carrier to effect release of the shipper, a normally reciprocating controller in sliding engagement with and supporting the dog in inoperative position, and means acting through the controller to lift the dog into the bunter path when a detector is released by its warp-thread.

5. In a loom, in combination, stop-motion detectors suspended by intact warp-threads, a vibrating feeler to engage and be arrested by a released detector, a controller connected with and reciprocating in unison with the movement of the feeler, a shipper, releasing means therefor including a normally quiescent and inoperative dog supported by and in sliding engagement with the controller, a bunter on a moving part of the loom, an actuator, a slip connection between it and the controller, to effect reciprocation of the controller and vibration of the feeler, arrest of the latter stopping reciprocation of the controller and disconnecting it from the actuator, continued movement of the latter lifting the controller to thereby move the dog into the path of the bunter.

6. In a loom, a shipper, releasing means therefor, including a dog and a rocking carrier on which it is pivoted, a bunter on a moving part of the loom, a controller in direct sliding engagement with and normally sustaining the dog out of the bunter path, the controller having a beveled seat, a vibrating actuator normally coöperating with the seat and effecting reciprocation of the controller, and means to stop reciprocation of the controller by or through failure of a warp-thread, the actuator at such time acting upon the beveled side of the seat and lifting the controller to position the dog in the path of the bunter.

7. In a loom, a shipper, releasing means therefor including a pivotally mounted, bod-

ily movable dog, a bunter on a moving part of the loom, a controller in sliding engagement with and normally sustaining the dog out of the bunter path, said bunter having a bevel-sided seat, a vibrating actuator normally engaging the seat to effect reciprocation of the controller, and means to arrest the controller by or through failure of a warp-thread, to effect disengagement of the controller and its actuator, continued movement of the latter lifting the controller to thereby raise the dog into the bunter path.

8. In a loom, a shipper, releasing means therefor including a pivotally mounted, bodily movable dog, a bunter on a moving part of the loom, a controller in sliding engagement with and normally sustaining the dog out of the bunter path, said controller having a V-shaped seat in its under side, a vibrating actuator having a roll in normal engagement with said seat to reciprocate the controller, and means to arrest the latter upon failure of a warp-thread, the roll on the actuator moving out of the seat and elevating the controller to operatively position the dog in the bunter path.

9. In a loom, a series of detectors suspended from intact warp-threads, a vibratable feeler to engage and be arrested by a released detector, depending supports for the feeler, fulcrumed at their upper ends, a vibrating actuator, a controller, a slip connection between it and the actuator, to normally reciprocate said controller, a connection between the controller and the feeler supports, to rock the same and vibrate the feeler, arrest of the latter stopping the controller and releasing it from the actuator, and shipper releasing means actuated by or through the controller when released from the actuator.

10. In a loom, a series of detectors suspended from intact warp-threads, a vibratable feeler to engage and be arrested by a released detector, a vibrating actuator, a controller, a slip connection between it and the actuator, to normally effect reciprocation of the controller by the actuator, a connection between the feeler and the controller, to vibrate the feeler, arrest of the latter stopping the controller and disconnecting it from the actuator, continued movement of the latter moving the controller transversely, a shipper, and releasing means therefor the operation whereof is effected by transverse movement of the controller when disconnected from the actuator.

11. In a loom, a series of detectors suspended from intact warp-threads, a vibratable feeler to engage and be arrested by a released detector, a vibrating actuator, a controller, a roll on one and a bevel-sided seat in the other, to normally coöperate and effect reciprocation of the controller, a connection between the latter and the feeler, to vibrate said feeler, arrest thereof stopping the controller

and disconnecting the roll from the seat, continued movement of the actuator effecting a transverse movement of the controller, and shipper releasing means operated by or 5 through such transverse movement of the controller.

In testimony whereof, I have signed my

name to this specification, in the presence of two subscribing witnesses.

ALONZO E. RHOADES.
